UNITED STATES PATENT OFFICE.

JOHN HOFFMAN, OF PORT HURON, MICHIGAN.

BARREL-STAND.

1,111,796.

Specification of Letters Patent. Patented Sept. 29, 1914.

Application filed March 11, 1912. Serial No. 682,873.

To all whom it may concern:

Be it known that I, JOHN HOFFMAN, a citizen of the United States, residing at Port Huron, in the county of St. Clair and State of Michigan, have invented certain new and useful Improvements in Barrel-Stands; and I do hereby declare the following to be a full, clear, and exact description of the invention, such as will enable others skilled in the art to which it appertains to make and use the same.

My invention relates to tilting barrel-stands, and has among other objects that of facilitating the handling of barrels or similar receptacles, and of dispensing liquid therefrom.

It also contemplates the production of a light, durable and inexpensive structure for the purposes stated, and one which is not likely to become deranged or get out of order.

The invention will be hereinafter particularly described and set forth in the claims following.

In the accompanying drawings which form part of this application, and whereon corresponding numerals refer to like parts wherever they occur in the several views: Figure 1 is a perspective view of the structure completely assembled and ready for use. Fig. 2 is a side elevation of the invention with the outline of a barrel in position for tilting, and Fig. 3 is a view corresponding with Fig. 2, except that the barrel has been tilted to a horizontal position, while the dotted lines of this figure indicate the barrel in course of tilting.

Reference being had to the drawings and numerals therein, 1 represents a circular base in the form of an annulus, mounted upon caster wheels 2 of any approved construction, and provided at points diametrically opposite with uprising vertical standards 3, 3 each rigidly secured to the said base 1 and notched at their upper extremities as at 4, 4. Resting loosely in each of said notches 4, 4 are pintles or trunnions 5, 5 projecting laterally from a barrel-supporting frame thus adapted to swing between the upright standards 3, 3 aforesaid, as best shown by Fig. 1 of the drawings. This frame is by preference of wrought iron and comprises a substantially V-shaped yoke or forging 6 inverted and slightly curved so as to conform in shape to that of the exterior of a barrel or other receptacle

which it is designed to embrace; at its apex or upper extremity it is provided with a pivotally connected hand-lever 7 serving at times also for a supporting-prop as indicated by Fig. 3; and at each side of this frame immediately below its supporting trunnions 5, 5 it is bifurcated, terminating in oppositely arranged forward and rearward struts 8, 9, respectively, the latter being slightly longer than the former and all four having inwardly turned angular lower extremities 10, upon which rest, and to which are securely bolted, an open frame-bottom 11 also by preference, though not necessarily, of annular form. For purposes of rigidity, and as a means of guiding a barrel into its proper position within said frame, there is secured to its bottom 11 at opposite points, a pair of parallel tracks 12, 12 crossing the base from front to rear practically in the same plane and serving to conduct barrels or other receptacles safely across the intervening space. For purposes of rigidity also, and as a means of effectually arresting a barrel when it has reached its final position in the barrel-frame, the rearwardly extending struts 9, 9 are connected by a curved band 13 describing the quadrant of a circle and securely fastened as by rivets 14, 14.

This being a description of my invention in its preferred form of construction its uses and operation are self-evident and need not be herein dwelt upon except in so far as it may be noted that the normal position of the barrel-stand, when not in use, is substantially that indicated by Fig. 1, its tilting-frame occupying a vertical position always ready for the reception of a barrel. And in the operation of placing a barrel in the position upon frame-bottom 11 indicated by Fig. 2 of the drawings, the parallel rails or tracks 12 perform the important function of skidding it over the intervening open space to a position where it is arrested by the back-strap or curved band 13. In this relation of barrel and frame it will be further noted that the trunnions 5, 5 occupy a position slightly below the center of gravity of the loaded barrel which may then be readily lowered to the position indicated in Fig. 3 by agency of the hand-hold or hand-lever 7 and thereafter supported upon the latter as shown. Moreover, when it is desired to completely drain the barrel of its contents the said lever 7 may be folded back-

ward under the truck thereby permitting the front end of the barrel to descend still lower until it engages and rests upon the front edge of the circular base 1.

5 This being a description of my present invention what I now claim and desire to secure by Letters Patent is:

1. In a tilting barrel stand the combination with a base, of a barrel frame pivotally 10 surmounting said base having an open bottom, tracks crossing said bottom from front to rear, a yoke having bifurcated lower ends secured to said bottom and adapted at its upper end to embrace the upper rear portion of a barrel, and a hand-lever pivotally 15 suspended from the upper portion of said yoke.

2. In a tilting barrel stand the combination with a base, of a barrel frame pivotally 20 surmounting said base having an open bottom, tracks crossing said bottom from front to rear, a yoke consisting of spaced members

adapted to permit protrusion of the convex portion of barrels consigned thereto and having bifurcated lower ends secured to said 25 bottom, and a hand lever pivotally suspended from the upper portion of said yoke.

3. In a tilting barrel stand the combination with a base of a barrel frame pivotally 30 surmounting said base having an open bottom, tracks crossing said bottom from front to rear, a yoke consisting of oppositely disposed converging side members spaced and adapted to permit protrusion of the convex portion of barrels consigned thereto, said 35 yoke having bifurcated lower ends secured to said bottom member, and a hand lever projecting from the back of said yoke.

In testimony whereof I affix my signature, in presence of two subscribing witnesses,

JOHN HOFFMAN.

Witnesses:

MABEL G. ROBINSON,
REBECCA HOFFMAN.
